UNITED STATES PATENT OFFICE.

LEWIS H. CHURCH, OF STAMFORD, CONNECTICUT.

DEVICE FOR FORMING STANDARD ELBOWS IN ELECTRIC CONDUITS OR OTHER PIPES.

SPECIFICATION forming part of Letters Patent No. 784,471, dated March 7, 1905.

Application filed November 14, 1903. Serial No. 181,221.

To all whom it may concern:

Be it known that I, LEWIS H. CHURCH, a citizen of the United States, residing at Stamford, in the county of Fairfield and State of Connecticut, have invented certain new and useful Improvements in Devices for Forming Standard Elbows in Electric Conduits or other Pipes; and I do hereby declare the following to be a full, clear, and exact description of the invention, such as will enable others skilled in the art to which it appertains to make and use the same.

My present invention relates to improvements in pipe-bending devices, and particularly to conduit-elbow formers.

Some of the objects of the invention are to provide an elbow-former of simple construction and few parts, to shape standard elbows with accuracy at any desired point in a length of pipe or conduit for electric conductors or other purposes, whether straight or provided with other elbows and without flattening or crimping the same, to provide a bending device which may be easily and speedily manipulated and will not allow the conduit or pipe to slip while being worked, and to provide a device into which the conduit or pipe may be inserted sidewise and the location of the bend may be accurately predetermined.

With these and other objects and advantages in view my invention consists in the novel and useful combination and arrangement of parts described and illustrated, and more particularly pointed out in the claims forming a part of the following specification.

In the drawings accompanying this specification and illustrating my invention, Figure 1 is a perspective view of the device, showing a conduit or pipe bent therein. Fig. 2 is a plan view thereof. Fig. 3 is a sectional view on line 3-3 of Fig. 2, and Fig. 4 is a side elevation.

Like letters of reference denote like parts in all of the figures of the drawings.

A is a form to be bolted to the work-bench or other stationary base, preferably in a horizontal position, by means of bolts a , passing through the bolt-holes a' . This form A may be constructed of heavy cast-iron and is pro-

vided with a rounded forming-corner a^2 , 50 curved on the arc of a circle, preferably conforming to the curvature in the bends of standard elbows for electric conduits or other pipes. A groove a^3 is constructed in the form A and extends along the front edge thereof 55 around the curved forming-corner a^2 and on the side of the form, where it ends and forms the stationary jaw of the clamp B a short distance from the termination of the curved forming-corner. The curvature of the groove 60 a^3 is sufficiently large to seat various-sized conduits or pipes to be bent.

C is a swinging arm pivotally mounted at c , the center of the arc of the forming-corner a^2 . Said arm is formed with a sleeve which 65 fits upon the stud-shaft c^6 , projecting from the under side of the form A, and at its opposite end said arm is of tubular shape and provided with a threaded socket c' , into which is fitted an operating-lever C' of suitable length. A 70 short integral opposing arm c^2 projects from this end of the arm C and parallels the same. A bolt c^3 passes through registering bolt-holes c^4 in the end of the short arm and the side of the opposing arm, and on the same is journaled 75 the grooved forming-wheel c^5 , which is in a plane with the grooved form A.

On the side of the form A where the groove a^3 terminates and serves as a jaw for the clamp are two lugs b , spaced apart and provided 80 with bolt-holes b' , through which passes the bolt b^2 . Pivotally mounted upon this bolt is a clamp B, to which is secured, by means of the screw b^3 , a removable jaw b^4 , which said jaw is provided with an angular groove b^5 , 85 opposing the curved groove in the form A. This jaw may be replaced by others with various sized and shaped grooves therein to accommodate different sizes of conduits or pipes. The clamp is formed with a tail b^6 , which is engaged by an eccentric b^7 , operating in a rectangular opening or slot b^8 through the form A, and said eccentric is pivotally mounted on a bolt b^9 , secured in lugs b^{10} integral with the form A on each side of the said slot or opening. Said eccentric is provided with a grasp or handle b^{11} . When this eccentric is operated, the jaw b^4 is forced positively toward

the opposing form A and locked and a conduit or pipe held securely in place, while the former-wheel c^5 is brought into engagement with the conduit or pipe and forms the elbow 5 or bend therein. After bending the lever C' is thrown back, the eccentric withdrawn from engagement with the tail of the clamp, and the latter by its own weight automatically drops away from the conduit or pipe, and the 10 latter may be quickly withdrawn and another conduit inserted to be bent.

A gage D is secured to the form, by means of which the position of the elbow to be formed in the conduit or pipe may be accurately fixed. 15 It is a rod bent at right angles near one end, and the bent end d is inserted in a hole or socket in the form A. The gage is held in place by the flat spring d' , which is secured to a lug projecting from the form on its upper 20 side, and the free end of said spring is bowed to engage with the gage and hold it in position for measurement. The gage may be thrown out of position by hand or by contact with the arm c^2 as the lever C' is brought 25 around. This gage is provided with suitable marks or indicia at predetermined distances thereon, and said marks, $x x'$ for one size of conduit and $y y'$ for another size, when registering with lengths marked off on the conduit 30 or pipe to be bent accurately indicate the proper position of the conduit or pipe in the form to produce an elbow therein at a given distance from either end of said conduit or pipe as shown by said marks.

35 Having thus fully described my invention, what I claim as new, and desire to secure by Letters Patent of the United States, is—

1. In a device for forming elbows in conduits or pipes for electrical or other purposes, the 40 combination with a form around which the conduit or pipe is adapted to be bent, a swinging arm provided with a revolute bending device, adapted to follow the curvature of the form and bend the conduit or pipe to conform 45 thereto, a gravity-jaw pivotally connected to the side of the form and lying normally in an open position, the said jaw forming, in conjunction with the side of the form, a vise-like 50 mouth adapted to grip a conduit or pipe, laid lengthwise therein, and a device adapted to

close said jaw and lock it in engagement with the conduit or pipe.

2. In a device for forming elbows in conduits or pipes for electrical or other purposes, the combination with a form around which the conduit or pipe is adapted to be bent, a swinging arm provided with a revolute bending device, adapted to follow the curvature of the form and bend the conduit or pipe to conform thereto, a clamp pivotally secured to said form and arranged to receive various sizes of conduits or pipes sidewise, a removable jaw, and an eccentric adapted to bear against said clamp and lock the same in engagement with the conduit or pipe, the said clamp having its 60 weight distributed so as to unlock by gravity when the eccentric is disengaged therefrom. 65

3. In a device for forming elbows in conduits or pipes for electrical or other purposes, the combination with a form around which the conduit or pipe is adapted to be bent, a swinging arm provided with a revolute bending device, adapted to follow the curvature of the form and bend the conduit or pipe to conform thereto, a clamp pivotally secured to said form 70 and provided with a removable jaw coöperating with a stationary jaw on the form to receive and retain conduits or pipes of various sizes, said conduits or pipes being clamped therebetween, an eccentric adapted to bear 75 against the pivotal clamp and lock the same in engagement with the conduit or pipe, the said clamp being weighted to unlock by gravity when the eccentric is disengaged therefrom and a gage consisting of a pivotal arm 80 mounted on said form and adapted to maintain a position parallel to the conduit or pipe to be formed with an elbow and indicia on said gage at predetermined distances and designed to register with marks placed on the 85 conduit or pipe and indicating the distance from either end thereof for the formation of the elbow. 90

In testimony whereof I affix my signature in presence of two witnesses.

LEWIS H. CHURCH.
